UNITED STATES PATENT OFFICE

2,421,899

FUEL INJECTOR PUMP STRUCTURE

Carlton Messner, Muskegon, Mich., assignor to
 Continental Motors Corporation, Muskegon,
 Mich., a corporation of Virginia

Application February 6, 1945, Serial No. 576,381

3 Claims. (Cl. 103—154)

1

This invention relates to engines of the fuel injection type, and is more particularly related to the injector construction.

Most injectors employed with fuel injection engines comprise complicated structures, and consequently they cannot be economically produced, nor do they lend themselves readily to production manufacture.

It is an object of the present invention to construct an improved injector by providing a simplified construction that is applicable to production manufacturing with a minimum of time and labor, thus providing a device which can be very economically produced.

More particularly, it is the object of the present invention to construct an improved injector by incorporating improved inlet and outlet valve structures of simple construction and which are interchangeable, one with the other.

Another particular object of the present invention is to construct an improved injector comprising a pump actuated directly by a cam and embodying means associated with the pump plunger for sealing the device against leakage of any of the fuel.

For a more detailed understanding of my invention reference may be had to the accompanying drawings illustrating a preferred embodiment thereof in which like parts are referred to by like reference characters throughout the several views, and in which:

Fig. 1 of the drawing comprises a vertical sectional view of an injector pump incorporating the principles of the present invention.

Fig. 2 is a detailed cross-sectional view through a valve, and taken substantially on the line 2—2 of Fig. 1, and

Fig. 3 is another cross-sectional view showing the pump plunger sealing means, and taken on the line 3—3 of Fig. 1.

The present fuel injector pump is designed to be directly attached to an engine casing 10, the injector pump housing 11 being bolted or otherwise secured to the engine casing as at 12. A cam shaft is supported by said engine casing and carries a cam 13.

The under face of the injector pump housing 11 is bored out and tapped as at 14 to receive a pumping instrumentality designated as a whole by reference character 15. This pumping instrumentality comprises a pump casing 16 provided with an enlarged flanged base portion 17 seating on a gasket 18 in the bottom of said bored recess 14. An externally threaded nut 19 is threaded into the bored and tapped recess of the

2

injector pump housing, said nut seating on the flanged base portion 17 as at 20 to secure said pump casing to the housing.

A pump plunger 25 is slidably supported in the internal bore 26 of the pump casing, and preferably comprises a drill rod, same being machined and ground to have a fairly close fit in said bore 26. A cup shaped tappet 27 telescopes on the external surface of the pump casing, said 5 pump plunger having a collar or sleeve 28 welded or otherwise permanently secured to the end of the plunger, and engaged by said tappet to advance the pump plunger when actuated by the cam 13. A spring 29 urges the tappet and plunger 10 to a retracted position, said spring seating on a gland 30 against the pump casing and a collar 31 seating on the collar 28. The pump casing 16 is recessed as at 35, about the pump plunger and the collar or gland 30 is also recessed as at 36. A flexible and resilient gland 37 is enclosed 15 in the recess 35, the enlarged flanged portion 38 of the gland 37 being clamped between the collar 30, and the end face of the pump casing by said spring 29. Said gland 37 is internally bored 20 and closely fits around the stem of the pump plunger 25, the inner end of this gland being chamfered or bevelled as at 40 so that any fuel pressure that may leak along the plunger into the chamber 35 under pressure, will exert a force 25 against this bevelled face of the gland, this force resolving itself into component forces directed respectively axially of the plunger and radially inwardly thereof, thereby causing the gland to contact more closely with the sliding plunger and effectively seal against escape of the 30 fuel along the plunger.

The injector is provided with an inlet valve 50 and an outlet valve 60, each of said valves comprising identical valve casings 70 each having a passage 71 controlled by a spring pressed ball valve 72. A stop 73 is assembled to the valve casing to limit the opening movement of the ball valve. The injector housing is bored as at 80 for receiving the inlet valve structure and as at 81 for receiving the outlet valve structure. The inlet valve 50 is so arranged as to allow fuel flow into the pump chamber 90 on the suction stroke of the pump plunger. The outlet valve 60 is reversed with respect to valve 50 and is so 40 arranged as to close on the suction stroke of the plunger and to open on the delivery stroke thereof. A coupling or union is threaded into the enlarged tapped bores 70a to assemble said inlet and outlet valves in place. 45 These inlet and outlet valves are thus inter-

changeable one with the other, and consequently provide for a more economical manufacture. These valves are readily and easily assembled with a minimum of labor. The complete injector pump comprises a unit structure of simple construction which is applicable for assembly with a fuel injection engine with minimum expense. Furthermore, this construction is very compact and is particularly suited for direct assembly with the engine.

Although I have illustrated but one form of my invention and have described in detail but a single application thereof, it will be apparent to those skilled in the art to which my invention pertains, that various modifications and changes may be made therein without departing from the spirit of my invention or from the scope of the appended claims.

I claim:

1. A fuel injector comprising a casing having a fuel inlet passage and a recess with which said inlet passage communicates, a pump body seated in said recess and provided with a pump cylinder aligned with the inlet passage in said casing, said pump body having a flange, a nut threaded into said recess and engaging the flange to secure said pump body to said casing, a pump plunger operable in said pump cylinder, a tappet guided on the external surface of said pump body and engaging said pump plunger, and means actuating said tappet.

2. A fuel injector comprising a casing having a fuel inlet passage and a recess with which said inlet passage communicates, a unitary pump assembly removably secured in said recess and comprising a pump body provided with a pump cylinder aligned with the inlet passage in said casing,

a pump plunger operable in said pump cylinder, said pump body comprising a barrel tappet guide, a tappet guided by said tappet guide and engaging said plunger, and means actuating said tappet.

3. A fuel injector comprising a casing having a cylindrical axial bore providing a pump chamber, a plunger guided in said bore, and projecting rearwardly beyond the end of said casing, said casing having a counterbored recess, a flexible sleeve associated with said plunger and having a tubular projection embracing said plunger and housed for the most part in said recess, said sleeve constructed and arranged to be urged radially inwardly against said plunger to grip same when subjected to fuel back pressure which leaks past said plunger into said recess, spring means for retracting said plunger, said sleeve having a flange seating against said casing, a gland seating on said sleeve flange, said spring yieldingly urging said gland against said sleeve flange to urge same into sealing engagement with the end of said casing.
